UNITED STATES PATENT OFFICE.

GEORGE W. KEELER, OF ANADARKO, OKLAHOMA.

GAME APPARATUS.

Application filed January 15, 1924. Serial No. 686,404.

To all whom it may concern:

Be it known that I, GEORGE W. KEELER, a citizen of the United States, residing at Anadarko, in the county of Caddo and State of Oklahoma, have invented certain new and useful Improvements in Game Apparatus, of which the following is a specification.

This invention relates to an improved game apparatus and seeks to provide an apparatus embodying a table having permanently mounted at one end thereof a set of pivoted ten pins and wherein a suitable ball, such as a billiard ball, may, by means of an ordinary cue, be driven down the table for overthrowing the pins.

The invention seeks, as a further object, to provide a game apparatus wherein the ball will be automatically returned to the player.

And the invention seeks, as a still further object, to provide an apparatus wherein the player may, without leaving his position, readily reset the pins.

Other and incidental objects will appear hereinafter.

In the drawings:

Figure 1 is a side elevation of my improved game apparatus,

Figure 2 is a top plan view of the device,

Figure 3 is an enlarged detail plan view of the pin supporting frame, particularly illustrating the mounting of the pins thereon as well as illustrating the mounting of the setter mechanism for the pins,

Figure 4 is an enlarged detail sectional view on the line 4—4 of Figure 3, looking in the direction of the arrows,

Figure 5 is an enlarged detail sectional view on the line 5—5 of Figure 4, looking in the direction of the arrows, and

Figure 6 is a detail sectional view on the line 6—6 of Figure 3.

In carrying the invention into effect, I employ an oblong table 10 having upstanding side and end boards 11 while at the rear end of the table is provided a trough 12 inclining toward a returnway 13 mounted at one side of the table to incline downwardly to the forward end thereof, the returnway being provided at its forward end with an appropriate stop 14. Straddling the table near the rear end thereof are spaced upstanding brackets 15 and 16 appropriately secured at

their ends to the side boards of the table and suspended by said brackets in spaced parallel relation to the table is a pin supporting frame 17. As brought out in Figure 3 of the drawings, the frame 17 is substantially V-shaped and is secured at its ends to an end bar 18, and extending through said bar near its extremities are parallel hanger rods 19 freely accommodated through the bracket 15. Screwed upon the upper ends of said rods are nuts 20. Engaged with the forward end of the frame is a similar hanger rod 21 which is freely accommodated through the bracket 16 and screwed upon the upper end of said rod is a nut 22. Thus, the rods 19 and 21 will serve to rigidly support the frame 17 above the table while the nuts 20 and 22 of said rods may be adjusted for elevating or lowering the frame to the exact position desired. Extending transversely between the sides of the frame are spaced parallel cross bars 23 secured at their ends to said sides, as shown in detail in Figure 6, by hook bolts 24 and mounted upon said bars to project forwardly therefrom is a plurality of U-shaped brackets 25, the ends of which are, as best seen in Figure 4, provided with eyes 26. Securing each of the brackets is a pair of bolts 27 and mounted upon the cross bars 23 between said pairs of bolts are forwardly projecting yieldable stop members 28 which may be of leather or other suitable material. Removable extending through the sides of the frame 17 and through the eyes 26 of the brackets 25 are cross rods 29 and swingingly mounted upon said rods between the arms of said brackets is a set of miniature ten pins 30. Inserted through the pins 30 to accommodate the rods 29 are, as shown in Figure 3, bushings 31 and these bushings extend at the sides of the pins to abut the eyes 26 of the brackets 25 for centering the pins between the arms of said brackets. Extending from the upper end portions of the pins are laterally directed studs 32 displaced rearwardly with respect to the longitudinal center line of the pins and mounted upon the cross bars 23 to coat with said studs are flat retaining springs 33 for the pins. As brought out in Figures 3 and 4, some of said springs are secured by the hook bolts 24 and other of said springs by the bolts 27, while for the spring of the

2
foremost of the pins 30 is provided a cross bar 34. This cross bar is similar to the cross bars 23 and is secured in like manner by hook bolts 35. At their rear end portions, 5 the springs 33 overlie the studs 32 so that the springs will serve to yieldably retain the pins 30 in vertical set position abutting the stop members 28, the forward end edges of said members being curved to fit the contour 10 of the pins. In this connection, it is to be observed that when the pins are set, the studs 32 are disposed rearwardly of the pivotal centers of the pins so that the springs may thus effectively cooperate therewith to prevent accidental forward tilting of the pins. 15

Slidably resting upon the cross bars 23 of the pin supporting frame is a substantially V-shaped pin setter 36, the sides of which, at the rear end of the setter, are 20 merged into a rearwardly directed shank 37 slidably received through the rear end board of the table and extending transversely between the sides of the setter are cross rods 38 extending in front of the pins 30 while 25 near the rear end of the setter is provided a light brace rod 39. The front cross rod is, as brought out in Figure 4, provided with a depending eye 40 and secured at one end to said eye is a retracting spring 41, the opposite end of which is attached to the forward end of the frame 17. Thus, the spring 41 will normally hold the pin setter in a forward position having the rods 38 thereof spaced forwardly from the pins 30. Pivotally 30 mounted upon the rear end board of the table 10 is, as best seen in Figure 4, a lever 42, the upper end of which is connected to the shank 37 of the pin setter and attached to the lower end of said lever to extend forward to the front end of the table is a reach rod 43 disposed beneath the table. Mounted at the forward end of the table is a block 44 upon which is pivoted an upstanding hand lever 45 to which the rear end of the 35 reach rod 43 is connected. Thus, the upper end of the lever 45 may be grasped when, by pulling forwardly thereon, the pin setter 36 will be shifted rearwardly against the tension of the spring 41.

50 In conjunction with the table and pins, I employ a ball 46 such as an ordinary billiard or pool ball. In using the apparatus, this ball is placed near the forward end of the table and, by means of an ordinary billiard or pool cue, is driven down the table to strike the pins, the object being to overthrow as many of the pins as possible. Upon reaching the rear end of the table, the ball will, of course, drop into the trough 12 to 55 enter the returnway 13 and return to the forward end of the table. When the ball 46 strikes the pins, the pins will, as shown in dotted lines in Figure 4, be swung to a forwardly inclined position having their rear ends elevated above the table a distance

sufficient to clear the ball so that any of the pins overthrown will not hinder the movement of the ball to strike any of the pins which remain set. After the pins have been overthrown, the hand lever 45 is operated, 70 as previously described, for shifting the pin setter 36 rearwardly and again setting the pins. Upon the rearward movement of the pin setter, the rods 38 thereof will be shifted against the upper end portions of the pins 75 for rocking the pins rearwardly to vertical position so that the pin setter will thus function to set all of the pins simultaneously. Upon release of the hand lever 45, the spring 41 will, of course, retract the pin setter to 80 normal position.

Having thus described the invention, what I claim as new is:

1. A game apparatus including a table, spaced brackets upstanding therefrom, a frame, rods suspending the frame from said brackets above the bed of the table, a set of pivoted pins carried by the frame in juxtaposition to the bed of the table whereby the pins may be struck by an object traveling upon the table bed for overthrowing the pins, and means for setting the pins. 85

2. In a game apparatus, a frame, a cross bar carried thereby, a bracket mounted upon the bar and having spaced sides provided with eyes, a cross rod upon the frame extending through the eyes of said bracket, and a pin pivoted upon the rod between said eyes. 95

3. In a game apparatus, a frame, a cross bar carried thereby, a bracket mounted upon the bar and having spaced sides provided with eyes, a cross rod upon the frame extending through the eyes of said bracket, a pin pivoted upon the rod between said eyes, 100 and a yieldable stop member mounted upon said cross bar for limiting the pin in vertical set position. 105

4. In a game apparatus, a frame, a set of pivoted pins carried thereby and tiltable 110 forwardly upon the frame, and a setter associated with the frame and having cross rods to extend in front of the pins, the setter being slidably rearwardly to engage said rods with the pins and swing the pins rearwardly to set position. 115

5. In a game apparatus, a frame, a cross rod carried thereby, a pin pivoted upon said rod, and a bracket carried by the frame and provided with spaced sides straddling the 120 pin adjacent the pivotal axis thereof to constantly coat with the pin for limiting the pin against movement along the rod.

6. In a game apparatus, a frame, a cross rod associated therewith, a pin pivoted upon 125 said rod, a bracket carried by the frame and having spaced sides straddling the pin and limiting the pin against movement along the rod, a stud projecting from the pin, and a flat spring secured at one end and having 130

its opposite end free to bear against said stud for yieldably holding the pin set.

7. In a game apparatus, a substantially V-shaped frame, spaced cross bars carried thereby, cross rods extending transversely of the frame adjacent said bars, a set of pins pivoted upon said rods, brackets secured to

the cross bars and having sides straddling the pins and limiting the pins against movement along the rods, and a flat spring associated with each of said pins normally holding each of said pins set. 10

In testimony whereof I affix my signature.

GEORGE W. KEELER. [L. s.]
